UNITED STATES PATENT OFFICE.

AUGUST A. WIMMERS, OF DAYTON, OHIO, ASSIGNOR TO THE EGRY REGISTER COMPANY, OF DAYTON, OHIO, A CORPORATION OF OHIO.

AUTOGRAPHIC REGISTER.

Application filed July 2, 1920. Serial No. 393,489.

To all whom it may concern:

Be it known that I, AUGUST A. WIMMERS, a citizen of the United States, residing at Dayton, in the county of Montgomery and State of Ohio, have invented certain new and useful Improvements in Autographic Registers, of which the following is a specification, reference being had therein to the accompanying drawing.

10 This invention relates to improvements in autographic registers.

Heretofore in this art the strips of paper supplied from one or more rolls have been fed through the machine and the rolls revolved to give off the paper by means of instrumentalities which pulled upon the paper forcefully enough to revolve the rolls and advance the paper through the machine. Under these constructions the paper was subjected to strain and tension sufficient for these dual purposes, namely, sufficient to revolve the rolls to unwind the paper and sufficient to advance the paper through the machine.

25 It is the primary object of this invention to do away with that system and to avoid submitting the paper to the excessive strains necessary to revolve the rollers and unwind the paper and also to feed the paper through the machine, as stated, the chief objection to which was the frequent tearing of the paper, to the serious inconvenience of the user.

In carrying out this primary object I provide the register with what may be termed dual paper-feeding mechanism, preferably operative from the same common actuating shaft, one branch of the mechanism acting to revolve the one or more rolls of paper to cause them to pay off these strips, and the other mechanism acting to feed through the machine the paper so paid off.

40 I preferably so adjust and coordinate these mechanisms that the paper shall be slightly slack between the two feeding mechanisms, so that while the paper will be paid off only as fast as it is fed through the machine, still there will be this slight slack in the paper to avoid subjecting it to the objectionable strains incident to the old method of feeding the paper in this class of registers.

45 Another object of my invention is to pro-

vide a removable section or unit comprising a frame, the paper rolls and the rotatable devices for rotating the rolls, such unit being made separate from the general casing and insertible in and removable from the casing for the purpose of convenience in use and economy in manufacture.

50 My invention also includes other objects, more or less of a structural character, as will more fully appear in the detail description to follow.

55 In the accompanying drawings:

Fig. 1 is a longitudinal, sectional view of my improved machine, taken centrally through it;

Fig. 2 is a transverse, sectional view taken on the line $y-y$ of Fig. 1 looking to the left;

Fig. 3 is a detail sectional view of one of the sprocket wheels used in the mechanism for rotating the paper rolls, on the line $z-z$ of Fig. 4;

Fig. 4 is an enlarged detail side elevation of a portion of that mechanism;

Fig. 5 is a vertical, longitudinal section of the machine, taken on the line $x-x$ of Fig. 2, looking toward the right;

Fig. 6 is a detail view showing the actuating shaft, its gear and associated parts, including the detent to prevent back-turning of the shaft;

Fig. 7 is a vertical, sectional view of a part of the casing and frame to show how they are connected;

Fig. 8 is a partial plan and sectional view on the line $8-8$ of Fig. 5 and looking in the direction of the arrow;

Fig. 9 is a detail plan view showing the stop for arresting the movement of the hand crank.

1 I designates any approved type of autographic register casing, such, for instance, as has long been used in the manufacture and sale of such registers by The Egry Register Company, my assigns. This casing includes a hinged end piece 2 by which access to the interior of the casing may be had and a pivoted cover or top plate 3, as also a tablet plate or support 4 for the paper strips at the place where they are written upon in recording transactions pertaining to sales.

10 In this casing I mount an actuating stud

shaft 5 operable by a hand crank 6 and carrying an actuating gear 7 which meshes with an idler pinion 8 mounted on a stud shaft 9 and meshing with a gear 10 carried on the paper feeding shaft 11. See Figs. 2 and 5, from which it will be understood that these several gears are mounted on one side of the casing. The shaft 11 extends across the casing and is supported on both sides, as seen in Fig. 2, and carries a pair of paper feeding rolls or drums 12 having tapered pins 13, preferably round in cross section. It will be noted that there are two of these paper feeding rolls so constructed. These feeding pins enter perforations formed along the margins of the strips of paper. The perforations are made in the paper preferably in conjunction with the printing of the blank forms commonly printed on paper for this purpose. The perforations are uniformly spaced apart and the pins are likewise uniformly spaced so that as the drums are rotated the pins successively enter the perforations and feed the paper forward or through the machine a distance substantially equal to the length of the circumference of the drums.

A suitable stop 14 limits each movement 30 to one complete rotation of the crank so that with each feeding operation the feeding drums and pins make one revolution. To prevent the crank being turned back and the paper thereby slackened or rumpled a 35 spring detent 15 mounted on one side of the casing engages with the actuating gear wheel 7.

The gear 10 while receiving motion from the pinion 8 transmits motion to a gear 16 40 which meshes with a gear 17 while it, in turn, meshes with a gear 18. These gears are all mounted on stud shafts 20 and their function is to transmit the motion they primarily receive from the actuating shaft 5 45 to the paper roll-operating devices, through a pinion 19, by which one or more paper rolls are rotated on their own axis and made to pay off the paper strips. This roll-operating mechanism consists, in the exemplification given in the drawings, of a series of 50 shafts 21, 22 and 23, one for each roll of paper, mounted in the removable frame 24 comprising a base piece and two side plates, as best seen in Fig. 2. On each of these 55 three shafts are secured two feed-rolls or disks 25 having their peripheries knurled or otherwise roughened or coated to cause them the more readily to take hold upon the paper rolls to frictionally rotate them. These 60 shafts have sprocket wheels 26 which are operated by a sprocket chain 27. The chain passes partially round the sprocket wheels on the shafts 21 and 23 and engages opposite sides of the sprocket wheel on the shaft 65 22. To properly keep the chain in position

with reference to this intermediate sprocket wheel I secure plates 28 to one side of the frame 24.

On the shaft 21 I mount the pinion 19 which meshes with the gear 18 and receives motion therefrom and acts to drive the chain 27 and thus rotate the shafts 22 and 23.

The effect produced by this rotation of these shafts is that of rotating the one or more rolls of paper. These rolls 30, 31, 32 75 each comprise a strip of many yards of paper with its margins perforated and wound upon a roller 33 whose supporting shaft 34 is fitted in slots 35 in the sides of the frame 24. In addition to the weight of 80 the rolls of paper, which causes them to press upon the disks 25, are spring-pressed arms 36 mounted on shafts 37 supported by the side plates of the frame 24 and provided with springs 38 each secured at one end to the side wall of the frame 24 and at the other end to the shaft 37 so as to exert a rotative influence on the shaft to cause the arms 36 to press downwardly on the shafts 34 and aid in keeping the paper rolls in 90 sufficiently firm contact with the feeding disks.

For convenience of lifting the arms 36 out of contact with the shafts 34 the ends of the shafts 37 are slotted, as shown at 95 39 in Figs. 5 and 8, these slots permitting of the use of a screw-driver to slightly rotate the shafts and lift the arms.

It will now be seen that when the actuating shaft and crank are given a rotative stroke the pin feeding roller will advance the paper one step through the machine while the disks 25 will be rotated through the intermediate gearing and endless chain and sprocket wheels to revolve the one or more paper rolls and pay off the paper. When the machine is adjusted for use the paper is fitted on the pins in a manner to leave a slight slack in the paper strips, as shown at points 40, 41 and 42. Then when the paper is fed the pins advance at substantially the same rate of speed as it is paid off from the rollers. In this way the slight slack is maintained and thereby the feeding strain by the pins on the paper is merely that required to move the paper along without the additional strain of unwinding the paper from the rolls.

This I regard as a distinct advance in this art and an important one tending to the greater ease of the operation of the machine and the avoidance of tearing or straining the paper and the pulling out of the short strips of paper between the perforations by the otherwise excessive strains exerted by the feeding pins.

And it will further be noted that the frame 24 comprises a separate unit together with the parts mounted therein, so that all these parts may be placed in their proper 130

position by the simple expedient of setting the frame at its place within the casing. It is there held by means of screws 43 which pass through the walls of the casing and 5 thence into the side plates of the frame 24, as seen best in Fig. 7. Lugs 44 properly space the frame and casing apart.

Paper supporting rolls 45 are mounted in the casing to support the webs of paper between the rolls and the tablet plate 4. At 10 the extreme end of the lid 3, beyond its opening 3^a, I fashion it to constitute a tear-off edge 3^b so that when the strips have been fed one step of the length of the printed 15 form they may be readily torn off. During the tearing off operation the paper is held from being pulled further through the machine by the engagement of the feed pins with the perforations therein, the hand 20 crank 6 at that time being in contact with the stop 14.

Referring to Fig. 3 it will be seen that the sprocket wheels 26 have their teeth slotted at 26^a to receive the links of the chain 25 27. In this way the chain is prevented from getting off of the sprocket wheels.

In this application I have shown and described one means of carrying out my broad invention of imparting rotation to the one 30 or more rolls of paper to pay off the paper without pulling on the paper webs for that purpose. I shall make herein generic claims to cover this invention. In my copending application filed Feby. 13th, 1920, Ser. No. 35 358,557, I have shown and described another mechanism for carrying out the same broad invention. In that application I shall claim that general type of mechanism, leaving, as stated, the generic claims to be claimed in 40 this application, as well as the particular form of one embodiment thereof.

Having thus fully described my invention, what I claim as new and desire to secure by Letters Patent, is:—

45 1. An autographic register comprising a casing having an opening and a paper support below the opening, a paper-feeding mechanism comprising a manually operated actuating device, a paper feeding device extending above the paper support to engage and feed the strips of paper a predetermined amount at each actuation of the actuating device, and co-acting devices to rotate the rolls of paper to cause them to pay off the same amount of the paper as is fed above the paper support.

55 2. An autographic register comprising a casing having an opening and a paper support below the opening, a paper feeding mechanism comprising a hand actuated paper feeding device which engages the paper strips above the paper support and acts to feed the same, and other devices actuated from the hand actuated device 60 which act to rotate the rolls of paper on

their axes an amount corresponding to the amount of paper fed over the paper support, and means to stop the hand actuated device when it has fed a predetermined amount of the paper.

3. An autographic register including a casing, comprising a lid having an opening therein, a paper support below the lid and paper-feeding devices extending above the paper support adapted to feed strips of paper through the register, paper rolls and a manually operated device to operate both the paper feeding devices and the rolls in unison to pay off and feed over the paper support the respective strips of paper.

4. An autographic register including a casing having a paper support below the casing top, and paper-feeding devices adapted to feed strips of paper over the paper support, of paper rolls and devices to operate the paper feeding devices and to rotate the rolls in unison to feed and pay off the respective strips of paper, and a tear-off edge on the casing top.

5. The combination, with a casing having a paper support, an actuating shaft, and a feeding roller provided with pins adapted to enter perforations in paper strips for feeding a fresh supply of paper above the paper support, of paper roll rotating devices, said feeding roller and said rotating devices being operatively connected with the actuating shaft, and a top above the paper support having a tear-off edge and an opening for exposing the paper.

6. The combination, with a casing having a paper support, a hand operable actuating shaft, and a feed roller adapted to engage a paper strip and feed it over the paper support, of a rotatable device and a paper roll supported on and rotated thereby, and suitable operative connections between the actuating shaft, the feeding roller and the rotatable device.

7. In an autographic register, the combination, with a casing, an actuating shaft, a pin feeding-roller, a series of shafts, disks mounted thereon, paper rolls resting on said disks, chain and sprocket devices connecting said disk shafts to cause them to rotate in unison, and gears connecting the actuating shaft with the feeding roller and the sprocket devices.

8. In an autographic register, the combination, with a casing, of a hand operable shaft, a pin feeding-roller geared thereto, a series of shafts each having disks and a sprocket wheel, a chain for said sprocket wheel, a series of gears between one of said shafts and the actuating shaft, slotted bearings over said disks, and paper rolls mounted in said bearings and resting on said disks.

9. An autographic register including a casing, a frame therein, shafts mounted in the frame, disks mounted on said shafts,

- means carried by the casing to operate the shafts and disks in unison, and paper rolls mounted in the frame and resting on and rotatable by said disks.
5. 10. An autographic register including a casing carrying paper feeding devices, a frame constituting a separate unit from the casing and adapted to fit therein, paper rolls mounted in said frame and roll-rotating devices also mounted in said frame and operable by the paper feeding devices and to rotate the rolls to pay off the paper.
11. An autographic register including a casing carrying paper feeding mechanism, a frame constituting a separate unit from the casing adapted to be inserted in and removed therefrom, shafts mounted in said frame, disks and sprocket wheels on said shafts, and a sprocket chain carried by said sprocket wheels, and operable from the paper feeding mechanism.
12. In an autographic register, a frame constituting a separate unit from the casing, slotted bearings therein, paper rolls mounted in said bearings, spring-pressed arms act-
- ing on the rolls, shafts carrying disks having roughened perforations on which the rolls press and from which they receive rotation, sprocket wheels on said shafts, and a sprocket chain working on said sprocket wheels.
13. In an autographic register, the combination, with a paper roll rotating shaft and disk, of a sprocket wheel mounted on the shaft and having its teeth slotted, and a chain whose links are adapted to enter said slots, the remainder of the teeth entering between the links of the chain.
14. In an autographic register, the combination, with a casing, an actuating shaft, a pin feeding roller and gears all mounted in the casing, of a frame constituting a separate unit insertable in and removable from the casing, roll-rotating disks having shafts mounted in the frame, said shafts being rotatably connected and one of them so connected to said gearing, and rolls of paper supported on and rotated by said disks.

In testimony whereof, I affix my signature.

AUGUST A. WIMMERS.
